UNITED STATES PATENT OFFICE.

MATTI VAARALA, OF PAINESDALE, MICHIGAN.

RESILIENT WHEEL.

Application filed August 24, 1923. Serial No. 659,182.

To all whom it may concern:

Be it known that I, MATTI VAARALA, a citizen of the United States, residing at Painesdale, in the county of Houghton and 5 State of Michigan, have invented certain new and useful Improvements in Resilient Wheels; and I do declare the following to be a full, clear, and exact description of the invention, such as will enable others 10 skilled in the art to which it appertains to make and use the same.

My invention relates to resilient wheels of the type in which shock-absorbing compression springs are interposed between a 15 felly and rim.

One object of the invention is to provide a novel arrangement of felly-carried cushioning springs and coacting rim-carrying plungers, and to mount the springs in a 20 unique manner to effectively anchor them, while permitting their outer end portions to compress and absorb shocks.

Another object is to place the convolutions at the inner portions of certain of the 25 springs, in tight contact with each other, thus forming cylinders in which the plungers operate, the inner ends of said cylinders being closed, whereby pneumatic cushions are formed, in addition to the cushioning action of the springs.

In mounting the springs, circumferentially spaced felly-carried, cylinder-forming blocks are employed, and a further aim is to make novel provision for rigidly holding 35 said blocks in properly spaced relation.

Yet another aim is to provide a rim formed of pivotally-connected sections associated in a novel manner with the plungers.

A still further object is to provide a 40 resilient wheel structure which will be comparatively simple and inexpensive, yet will be highly efficient and in every way desirable, the advantages of the pneumatic tire being obtained, without the use and disadvantages thereof.

With the foregoing in view, the invention resides in the novel subject matter herein- 45 after described and claimed, the description being supplemented by the accompanying drawings.

Figure 1 is a fragmentary longitudinal sectional view, partly in elevation.

Figure 2 is a transverse sectional view as indicated by line 2—2 of Fig. 1.

Figure 3 is a partial plan view of the pe-

riphery of the wheel, parts being broken away and in section.

In constructing the preferred form of my invention, which I have selected for illustration in the present application, I make 60 use of a channel-shaped metal felly which is designated in the drawings by the numeral 1. Snugly received between the side flanges 2 of the felly 1, at circumferentially spaced points, are a number of metal blocks 3 which 65 extend uninterruptedly from one of the flanges 2, to the other of said flanges. The outer ends of the blocks 3, are provided with circumferentially-extending lugs 4 which extend between the flanges 2, the lugs of each 70 block, being in contact with the adjacent lugs of adjacent blocks, as shown clearly Fig. 1. Spacers 5, preferably formed of wood, are interposed between the blocks 3, the outer portions of said spacers being in 75 contact with the inner sides of the lugs 4, and radial bolts 6 pass through the lugs and spacers and through the inner side of the felly 1.

In the present disclosure, each of the 80 blocks 3, is formed with a pair of radial openings 7, constituting cylinders for a pair of relatively large, radially positioned, coiled, compression springs 8. The cylinder-contained portions of the springs 8, have 85 their convolutions disposed in tight contact with each other and these convolutions contact tightly with the walls of the cylinders, so that the springs are effectively anchored. The convolutions beyond the blocks 3, how- 90 ever, are spaced apart so that the outer ends of the springs may compress to absorb shocks.

Disposed within the springs 8, are auxiliary cylinders 9, which contact with the inner sides of said springs, said cylinders 9 being secured to the felly 1, in a manner hereinafter described. Auxiliary compression springs 10 are tightly received in the cylinders 9 and have their cylinder-contained convolutions disposed in tight contact with each other. The other ends of the springs 10, however, project beyond the cylinders and beyond the springs 8 and have their convolutions spaced apart, permitting 105 them to compress and absorb shocks.

Radially disposed plungers 11 are slidably received in the springs 10 and are provided at their outer ends, with transverse plates 12, the ends of each plate being provided 110

with a pair of radially projecting lugs 13, for a purpose to appear. It may here be pointed out, that the plates 12 and plungers 11 move inwardly against the action of the 5 springs 10 only, when slight road roughness is encountered, and that under excessive jars, the plates 12 strike the relatively large springs 8 and thus bring them into play. In addition to these cushioning actions, attention is directed to the fact that the tightly coiled inner portions of the springs 10, form cylinders in which the plungers 11 operate, thus providing pneumatic cushions also.

Any desired means may be provided for 15 securing the cylinders 9 in place, but as it is necessary to provide for lubricating the plungers 11, I prefer to provide common means for securing the cylinders and permitting the lubricant to be injected. In the 20 present showing, cap screws 14 are passed through the inner ends of the cylinders 9 and are threaded through the felly 1, the inner ends of said screws being positioned in countersinks 15, in the felly. The screws 25 14 are formed with oil ports 16, and caps 17, within the countersinks 15, are normally threaded upon the screws to close said ports. By removing these caps however a quantity of oil may be injected through the ports 16, 30 to lubricate the plungers 11 and springs 10, thus insuring smooth and easy operation thereof.

While any adequate rim structure might be used in connection with the features above 35 described, I prefer to provide a rim formed of arcuate sections 18 having intermeshing knuckles 19 which rest against the outer sides of the plates 12, the knuckles of adjacent sections, being pivotally connected with 40 each other by pins 20 passing therethrough, the ends of the pins being in abutting relation with the lugs 13, so that the latter hold them against removal, as well as holding the entire rim structure against lateral shifting.

45 To permit the necessary relative movement of the sections 18, allowing the plungers 11 to move radially, certain of the openings in said sections, through which the pins 20 pass, are of elliptical form as indicated at 21. Any desired means may be employed to 50 prevent circumferential creeping of the rim, upon the plates 12, but for this purpose I have disclosed a rounded stud 22 on one of the plates 12, received rather loosely in a 55 socket 23 in the adjacent rim sections 18, it being understood that any desired number of studs and sockets may be used in the complete wheel.

60 Any desired form of tire (not shown) may be used upon the rim and will be held against lateral shifting thereon, by the projecting outer ends of the lugs 13. To permit the tire to be easily applied, it is necessary to first compress a number of the cushioning springs 8 and 10, permitting the di-

ameter of the rim to be decreased. To facilitate this operation, I have shown apertured lugs 24 on the ends of the plates 12, for engagement by any desired means for drawing said plates inwardly and holding them until the tire is applied.

65 By providing the construction shown and described or a substantial equivalent thereof, a spring wheel is provided which will be comparatively simple and inexpensive, yet it will be highly efficient and reliable. As excellent results may be obtained from the details disclosed, they are preferably followed, but within the scope of the invention as claimed, numerous minor changes may be 70 made.

75 I claim:

1. A resilient wheel comprising a felly-carried radial cylinder, a relatively large radially disposed coiled compression spring in 80 said cylinder contiguous to the walls thereof and extending beyond the same, an auxiliary cylinder secured in the first-named cylinder and disposed within said relatively large spring contiguous to the convolutions thereof, an auxiliary coiled compression spring in 85 said auxiliary cylinder contiguous to the wall thereof and extending beyond the outer end of the first-named spring, and a rim-carrying plunger slidable in said auxiliary spring and having a shoulder abutting the same, said shoulder being adapted to strike the relatively large spring under severe 90 shocks.

2. A structure as specified in claim 1; the 100 cylinder-contained portions of said springs having their convolutions in tight contact with each other.

3. A structure as specified in claim 1; the 105 cylinder-contained portion of said auxiliary spring having its convolutions in tight contact with each other to provide a cylinder for said plunger.

4. A resilient wheel comprising a felly-carried coiled compression spring disposed 110 radially, and a rim-carrying plunger slid- 115 able in said spring and having a shoulder bearing against the outer end thereof, the inner portion of said spring having its convolutions in tight contact with each other to provide a cylinder for the plunger, said cylinder being closed at its inner end.

5. A resilient wheel comprising a peripherally channelled felly, a plurality of circumferentially spaced cushion-carrying blocks in the channel of said felly having circumferentially projecting lugs at their outer ends, the lugs of each block abutting adjacent lugs of adjacent blocks, fillers in the 120 channels between said blocks and in contact with the inner sides of their lugs, and bolts passing through said lugs, fillers and felly.

6. A resilient wheel comprising spring-mounted felly-carried plungers having transverse plates at their outer ends, said 125

plates each having a pair of transversely spaced radially extending lugs, a plurality of rim sections extending between said plates and having intermeshed knuckles resting on said plates, pivot pins extending through said knuckles and abutting said lugs, and means for holding said rim sections against circumferential creeping on said plates, said lugs extending beyond said rim sections to retain a tire in place on the latter.

In testimony whereof I have hereunto affixed my signature.

MATTI VAARALA.
